CONCRETE STAIR MOLD

Frank Kogl, St. Paul, Minn., assignor of four per cent to Minnie M. Clark, South St. Paul, Minn.

Application April 16, 1941, Serial No. 388,772

14 Claims. (Cl. 25—118)

This invention relates to improvements in molds for precasting concrete stair structures.

The primary object of the invention is to provide a mold in which a selected number of steps may be cast in a monolithic unit and with side runners adapting the structure for use in lawn terraces. Another object is to provide a mold having provision for forming gutters alongside the steps and a transverse groove or channel adjacent the junction of each tread and riser, in such manner that water running from the steps will be conducted by said grooves toward the gutters to run out from the lower ends thereof. Another object is to provide a mold of this kind in which the width and height of the treads and risers, respectively, may be readily adjusted in order to vary the length and pitch of the stair. Still another object is to provide a mold in which the side runners may be readily cut away when it is desired to use the structure within a house, as for instance for basement or apartment stairs. Still a further object is to provide an improved means for mounting the upright posts of protective railings where such devices are desired.

These and other more detailed and specific objects will be disclosed in the course of the following specification, reference being had to the accompanying drawings, in which—

Fig. 1 is a perspective view of a step or stair structure particularly adapted for lawn or terrace use and having side runners and gutters.

Fig. 2 is a fragmentary plan view of the mold as set up for forming the structure of Fig. 1.

Fig. 3 is an enlarged cross section along the line 3—3 in Fig. 2, and showing the manner of supporting and disposing the railing mounting nuts in the mold.

Fig. 4 is a somewhat similar view but showing the lower portion of a railing post mounted on a fragment of a cast structure by means of the nuts shown in Fig. 3.

Fig. 5 is an enlarged longitudinal section through the mold showing the same in its inverted or casting position, and with the mold filled with a cementitious material.

Fig. 6 is a fragmentary end view, on an enlarged scale, looking at the intended upper end of the cast stair structure in the mold, and showing the end closures for the uppermost tread and the upper end of the side runner.

Fig. 7 is a perspective view of an end closure for the runner.

Fig. 8 is a diagrammatic side elevation indicating the manner in which stair structures cast in my mold may be connected together in end

to end relation where a greater number of steps may be required.

Fig. 9 is a view similar to Fig. 6, but showing end closures for the lower end of the casting and mold.

Fig. 10 is a greatly enlarged fragmentary longitudinal section through one tread and riser portion of the mold, showing the same reverted from its position in Fig. 5, and indicating in dotted lines the manner in which the treads and risers may be adjusted in width and height respectively.

Fig. 11 is a substantially vertical cross section taken through one side of the mold as shown in Fig. 10.

Fig. 12 is a perspective view of a stair structure cast without the side runners and gutters and particularly adapted for use as a basement stair or the like.

Fig. 13 is a view similar to Fig. 11 by showing the mold adapted for casting the structure of Fig. 12.

Fig. 14 is a fragmentary cross section through one side portion of the mold showing the lug and groove means for supporting the outer tread and riser form.

The mold of my present invention embodies features disclosed in detail in my copending application Serial No. 278,711, for a Method for precasting concrete stair structures; copending application Serial No. 287,513, for an Apparatus for precasting concrete stair structures, and my prior Patent No. 2,161,822, issued June 13, 1939.

Referring now more particularly, and by reference characters to the drawings, my mold includes as its primary parts, an outer or center form A and inner form B, and side forms C, all of which are shaped and adapted to mold the stair structure of Fig. 1 having the treads D, risers E, and side or runners F.

The outer form comprises a plurality of outer tread and riser forming members in the form of plate members 10, which are bent along longitudinal fold lines 11, to provide the tread and riser plates 12 and 13 disposed substantially at right angles to each other as shown. One plate 10 thus formed, is provided for each step and the length of the plates is such that they are just nicely fit between the side forms C. To make the plates extremely rigid I provide a plurality of L-shaped brace straps 14, which are welded or otherwise secured to the plates in spaced relation as clearly shown. Along each exposed edge of the plates 10, I provide inwardly spaced guard members or pieces 15 of angular

cross section having their ends or edges 17 turned angularly and slidably engaged with inner surfaces of the plates. The guard pieces 15 thus provide angular slide ways 19, which are adapted to receive the rigid connection angles designated at 20. The webs 21-22 of the angles 20 are disposed substantially at right angles to each other, and when entered into the slide ways 19, of adjacent plates 11 and 12 will so connect the plates that they will assume the stepped formation clearly shown. For fastening the assembled plates together, I provide stud bolts 23 which are welded or otherwise rigidly secured to the guard pieces 15 and passed outwardly through openings 24 (Fig. 10) in the angles 20 and through slots 25 in the plates 10 and straps 14. The slots 25, are elongated vertically on the risers and horizontally on the treads or in the direction of the straps 14 and, by adjusting the nuts 26 on the stud bolts 23, the plates 10 may obviously be spread apart at their adjacent edges in order to increase the effective width of the tread plates 12, and height of the riser plates 13. This adjustment is shown in dotted lines in Fig. 10, and it will be evident therefrom that the overall length of the cast unit of steps may thus be increased or decreased as may be required. Likewise by adjusting the effective area of either treads or risers either alone, or in certain proportions, the pitch of the cast structure may be varied within a considerable range.

The side forms C include the elongated flat side plates 27 which are rigidly braced by outer channels 28 and which are connected by transverse tie-rods 29. In setting up the forms, the assemble plates 10, in whatever adjustment may be selected, are disposed between the side plates 27 and the nuts 30 on the ends of the tie-rods 29 are drawn tight to thereby draw the side plates 27 against the ends of the plates 10. This fastening is made as near fluid tight as possible, and distortion of the side plates 27 is prevented by the aforesaid channel 28 and other brace members 31 in order to prevent the plates from sagging away from the outer step form. The plates 27 are considerably longer than the forms in order to provide space for adjustment of the form A.

Along the lower edges of the side plates 27, I provide flat bars 32 which are disposed flush with said edges and rigidly welded thereto and secured then to the outer surfaces of the bars 32 are the angle irons 33, which serve to mount the runner form portions of the mold but which depend below the lower edges of the bars 32 and side plates 27 in order to form the angular channels or grooves 34 as shown in Figs. 11 and 14. The angles 20 at the junction of their webs 21 and 22 are provided with endwise extended lugs 35 which are adapted to fit into the grooves 34 and slide freely therealong. In its casting position the mold is inverted as shown in Fig. 5, disposing the grooves 34 uppermost and thus the lugs 35 will serve to swingably support or suspend the plates 10 and associated parts of the outer step form A between the side forms. The lugs thus permit the adjustment of the tread and riser plates as heretofore described, meanwhile keeping all of the plates in proper alignment between the sides of the mold. The tie bars 29 are, of course, so located between the side plates 27 that they will not interfere with, or contact the outer form A, when such adjustments are made.

Attention is directed to the fact that the cor-

ners of the plates 10 and angles 20 are in each case rounded in order to provide a smoothly rounded contour for the step and likewise, at their extremities, the plates 12 are turned downwardly smoothly as shown at 36 in Fig. 11 in order to prevent the formation of sharp edges at the ends of the step treads.

It will further be noted that the inward spacing of the guard plates 15 will result in the formation of shallow grooves or channels 37^a of considerable width at the junction of each tread and riser. The channels 37^a thus formed in the risers E are of advantage in that they define a nosing 38^a along each tread in accordance with modern step construction. The channels 37^a in the treads also have an advantageous function as will presently appear.

In addition to the side plates 27, the side forms C each include the trough shaped runner forms 31 which are designated generally at 37, and which at their inner edges carry the rigidly mounted angle bars 38 adapted to be secured by means of bolts 39 with their horizontal webs in overlapping engagement with the outwardly turned webs of the aforesaid angle bars 33. The outer walls 40 of the forms 37 extend considerably above the lower edges of the side plates 27, in the casting position of the mold, while the inner wall 41, through the overlapping bars 38 and 39 are spaced substantially away from the side plates as best seen in Fig. 11. The runner forms 37 are rigidly braced by straps 42 and at outer edges carry the angle bars 43 which are welded in place and which have outwardly turned webs 44.

The inner form B is of sectional construction comprising for each step a trough-like member 45, formed of sheet material bent to provide inner tread and riser forming portions or plates 46 and 47, respectively. At their ends, the tread plates 46 of each of the members 45 are turned upward angularly as represented at 48 in order to bring the ends of the members out to a common plane of the edges of both plates 46 and 47. The length of the members 45 is such that, in the assembled position of the mold, the angularly bent ends 48 will stand well away from the side plates 27, as shown in Fig. 11, in order to permit the cementitious material to be filled out and around the angle bars 33 and 38, and into the runner forms 37, as will later appear.

Angle irons or cross bars 49 are welded, or otherwise rigidly secured, to the edges of the plates 46 and 47 and these angle irons extend crosswise of the mold outwardly into overlapping relation to the bars 43 on the runner forms 37. At their ends, the angles 49 are joined by tiebars 50, welded in place at their ends 51, and for each tiebar, I provide two set screws 52 which are threaded through the bars and may be brought to bear against the webs 44 of the angle bars 43 in the inverted casting position of the mold shown in Fig. 5. It will be evident that adjustment of the set screws 52 will permit the members 45 each to be raised and lowered toward and away from the outer form A to thus make thickness adjustments of the treads and risers of the stair structure.

It is understood, of course, that in assembling the form, the members 45 are disposed with their respective riser plates 46 and 47, substantially parallel to, and spaced from, the corresponding outer tread and riser plates 12 and 13 to provide casting cavities for the treads and risers. To prevent displacement of the members 45 I employ C-clamps 53 which may be hooked as shown

at 54 over the webs 44 of the angle bars and by adjusting the screws 55 of the C-clamps it will be evident that the tiebars 50 may be urged toward the angle bars 43. By locating the C-clamps between the respective pairs of set screws 52 for each tiebar, the clamps may act as pivots so that the members 45 may be rocked angularly about transverse axes by proper adjustment of the set screws. The purpose of this adjustment will be described hereinafter.

In the operation of the mold, it is inverted and reverted, and to facilitate such operation I provide end members 58 which join the side plates 27 and at their centers carry endwise extended pins 57. Bails or hangers 58 may be pivotally engaged with the pins 57 and, by the use of an overhead crane or lift (not shown) connected to the bails, the entire mold may be raised or lowered as required, and readily turned over about the axes of the pin with the outer form A assembled between the side plates 27 and locked at any desired adjustment.

The mold is first inverted as shown in Fig. 5, and the inner form members 45 put in place. It will be noted that the members 45, when properly installed, are spaced apart, as represented at 59, substantially along the junction of the treads and risers to thus provide spaces through which the cementitious material may be poured down into the cavities between inner and outer forms, and likewise the trough-like runner forms 37 now open upwardly in this position of the mold so that material can be poured directly thereto. The entire mold may thus be quickly and conveniently filled and by suitably vibrating the forms the material may be settled into place without the formation of voids or air bubbles.

Suitable reinforcing rods or grids 60 may be laid into the outer form before the inner form is put in place in order to provide added strength for the structure in accordance with usual practice.

The uppermost tread, or the space in which that tread is cast, must be closed at its end in order to prevent the escape of material thereat, and for this purpose I provide an end plate 61 (Figs. 5 and 6) which extends the full distance between the side plates 27. For mounting the end plate 61 the angle 20 inserted at the edge of the adjacent tread plate 12 has a downwardly turned web 62 against which the lower edge of the plate 61 is mounted and secured by means of bolts 63. Slots 64 in the plate 61 pass the bolts 63 and permit adjustment of the end plate to insure that it fully covers this open end of the mold. Closure members 65 are also provided at each end of the plate 61 and extend outwardly therefrom over the angle bars 33 and 38 and into the runner forms 37 to provide end closures for the runners in suitable alignment with the edge of the upper tread. For mounting the closures 65, I employ bolts 66 passed through the ends of the plates 61 and through slots 67 in tie plates 67^a on inner ends of the said closures, thus permitting adjustments to correspond with those of the end plate 61 itself.

Attention is directed to the fact that the end closures 65 have the angularly turned and articulated wings 68 which enter the runner forms 37 and extend first substantially parallel with the upper tread forming plate 12, and then curve out to meet the bottom walls 69 of the forms 37. The result of this shape and position of the wings 68 is shown in the rounded upper end portion 69 of the runners F in Fig. 1.

At the riser plate 13 forming the lowermost riser, in lieu of the angles 20 and guard member 15, I simply extend this plate 13 to such distance that it will extend substantially above the level 5 of the mold in its inverted position and then provide a flat end plate 70 (Figs. 5 and 9), fastened by bolts 71 and slots 72, to permit further extension if it may be required. This construction, of course, cuts off the lower rise flatly and at the 10 proper angle with respect to the lower tread as clearly shown in Fig. 1. However, I here again provide end closures 73, mounted upon the end plate 70, by bolts 74 and slots 75, and shaped and adapted to enter the runner forms 37 and cut the 15 runners off flush with lower riser.

Attention is directed to the fact that, toward their lower ends, the runners F curve outwardly to a point substantially flush with the lower tread as represented at 76 in Fig. 1. The runners thus 20 will start from a point substantially flush with the sidewalk against which the lower end of the steps are abutted, and when properly mounted, the upper edges of the runners will be substantially level with the lawn in order to prevent any 25 obstruction to the use of the lawnmower. Likewise of course, the upper ends of the runners will fall substantially flush with the walk leading to the house. The installation and mounting of the steps are not shown in the drawings since it is 30 well known in the art. To provide the foregoing rounded portion 76 of the runners, the runner forms 37 increase in depth toward their lower ends and the bottom walls 69 of the forms are curved, as best indicated at 77 in Fig. 5.

With the mold in its inverted position, the exposed upper edges along the spaces 59, and of course the upper open sides of the runner forms 37, may be readily smoothed off with a trowel to properly surface the outside of the structure. After 35 the material has thus been poured and smoothed off, the mold is allowed to stand until the material hardens, either naturally or through the application of steam for more rapid curing, and then the various end enclosures and the inner form members 45 are removed. The mold is then 40 reverted and lowered to a support upon which the cast structure may rest and the tie rods 29 are loosened so that the entire mold may be pulled from the casting. After the mold is removed, it is of course reassembled, ready for the 45 next operation.

The shape of the side forms C is such that a 50 gutter G is formed between the ends of the steps and the adjacent runners F by the angle bars 33 and 38 and innerwalls 61 of the forms 37. These 55 gutters G extend from end to end, or from top to bottom, of the stairs and will lead off any water leaves or similar materials from the steps down onto the sidewalk. The recesses or channels 37^a in each tread D, have an important function 60 in this respect. The water dripping from each tread to the channels therebelow will be conducted by the channels out to the gutters G and it is found that the outer tread plates 12, as they 65 support the cementitious mixture in the mold, have a very slight tendency to sag and thus they will slightly crown the channels causing them to slope from the centers to the ends of the steps to facilitate this action.

Obviously in setting up the mold, the end closures for the uppermost tread may be applied at any tread plate 12 to thus cut the steps off in any desired number. In making the aforesaid 70 adjustments of the width of the treads, and height of the risers, the inner form members 45

may be readily shifted back and forth in order to properly locate them with respect to the outer form and may of course be locked by the set screw 52 and C-clamp 53. Likewise, wherever necessary, the members 45 may be tilted or adjusted to vary the thickness and sectional shape of the treads and risers to best meet the stress requirements for steps of different sizes and lengths.

As heretofore stated, it is desirable to vibrate the mold as the material is poured, and in practice, I have found it best to apply this vibration directly to the inner form C. As an effective arrangement for this purpose I may connect the angle bars 49 with a removable channel or rigid bar 78 (Fig. 5) and upon this bar, I may mount any conventional form of vibrating device (not shown), one well known type being known to the trade by the name "Syntron."

Under some circumstances, it may be desired to anchor a number of my stair structures together in end to end relation thus providing a greater number of steps than can be conveniently handled and molded in one unit. To thus connect the steps, I may embed the elongated tubular members or pipes 80 in the runners F in the process of casting the strairs and permit the ends of the pipes to open at the ends of the structure as seen in Fig. 1. When adjacent step sections are then butted together they may be connected by inserting short lengths of pipe or sleeves 81 in the adjacent ends of the pipes 80 and anchoring them by pins 82 as best seen in Fig. 8. To pass the pins 82 tapered plugs 82a may be supported in the mold by screws 82b and when removed they will provide openings 33° through which the pins may be inserted. The openings may of course be plugged after the pins are in place. Or in lieu of the foregoing, a longer length of pipe may be telescoped through the pipes 80 as will be understood. In either case the joint between step sections may be filled with a caulking compound and the connecting pipes will of course additionally serve as reinforcing means for the steps.

It is frequently desired to mount railings upon the steps, and for this purpose I provide the device shown in Figs. 2, 3, and 4. Upon the outer form or the side form, at any desired locations thereon, I mount flat members 83, which are welded in place and have spaced openings 84 registering with similar openings in the adjacent wall of the mold. In initial setting up the mold, suspension bolts 85 are dropped through the openings 84 and nuts 86 are screwed on the ends of the bolts in such position that they will be supported adjacent to the inner form wall represented at 87 in Fig. 3. During the casting operation, the bolts 85 are retained rigidly in place by tapered wedges 88 placed through loops or clips 89 on the members 83 and bearing at their ends upon the heads of the bolts. Prior to removing the casting from the form, the wedges 88 are removed and the bolts 85 unscrewed, thus leaving the nuts 86 embedded in the concrete and forming passages 90 opening upwardly through the surface of the casting. The railing posts, as indicated at 91, are then provided with base flanges 92 having openings 93 to register with the passages 90 and mounting bolts 94 may be entered through the passages 90 and screwed into the nuts 86 to anchor the railing in place. To prevent the accumulation of water in the passages 90, the lower ends thereof may be drilled or knocked out, as represented at 95 in Fig. 4, and the passages 90

may if desired, be provided in all the castings and then plugged with cork or the like until their use is desired.

The stair structure with the runner is best adapted for outdoor use of course, but it may be used indoors for basement or apartment stairs or the like, and the sidewalls built up upon the runners. However, by removing the side forms C or, more specifically the troughlike runner forms 37, a structure of the kind shown in Fig. 12 having simply the straight lateral edges H may be cast. The mold thus arranged, is shown in Fig. 13 and it will be noted that the side plates 27 are extended by narrow auxiliary plates 96 which along one edge have the angle bars 97 adapted to be secured to bolts 98 to the hereinbefore described angle bars 33, thus disposing the plates 98 and 27 flush at their inner sides. The opposite edges of the auxiliary plates 96 also carry angle bars 99 for the mounting and adjustment of the cross bars 49 in the manner previously described. Hooks 106 may be embedded in the steps (Fig. 12) as an aid to mounting and supporting them.

It may be desirable in casting the structure of Fig. 12, to dispense with the adjustment of the risers i, but adjustment of the treads J is of advantage particularly in that it serves as a convenient means for varying the pitch also as shown in Figs. 10 and 12. I may employ small former or recessing plates 100 secured beneath the outer treads and form recesses 101 for the reception of non-skid, pads or mats 102, shown in Fig. 12.

It is understood that suitable modifications may be made in the structure as disclosed, provided such modifications come within the spirit and scope of the appended claims. Having now therefore fully illustrated and described my invention, what I claim to be new and desire to protect by Letters Patent is:

1. A mold for precasting a monolithic concrete stair structure having a plurality of steps, the said mold including members for forming outer surfaces of the treads and risers of the steps, and separate angle members adjustably connecting the tread and riser forming members to each other at the junction of the treads and risers and adjustable to permit variations in the height of the risers and width of the treads, the said tread and riser forming members having slideways to receive the said angle members.

2. A mold for casting a concrete stair structure having a plurality of steps, including an outer form made up of separable sections for each step, each of said sections having a riser forming portion and a tread forming portion disposed substantially at right angles to each other, angle members adjustably connecting the edge of each riser forming portion to the adjacent edge of each tread forming portion and permitting adjustment of the effective areas of said portions, and said angle members being arranged on the inner casting surfaces of the outer form.

3. A mold for casting a concrete stair structure having a plurality of steps, including an outer form made up of separable sections for each step, each of said sections having a riser forming portion and a tread forming portion disposed substantially at right angles to each other, angle members adjustably connecting the edge of each riser forming portion and permitting adjustment of the effective areas of said portions, and guard members arranged over the said angle members at inner sides thereof and slidably engaging in-

ner surfaces of the tread and riser forming portions.

4. A mold for casting a monolithic series of steps having treads and risers, comprising a sectional form adapted to define and mold outer surfaces of the treads and risers, angle members adjustably connecting the form sections adjacent the junctions of the treads and risers, and guard members slidably enclosing said angle members and disposed on the inner side of the form to thereby form channels in the treads and risers.

5. A mold for casting a series of concrete steps in a monolithic unit, comprising an outer form for defining the outer surfaces of the treads and risers of the steps, side members mounted on the said outer form, an inner form comprising a separate section for each step adapted to mold the inner surfaces of the treads and risers, and means adjustably connecting the said sections to the side members and permitting the sections to be adjusted toward and away from the outer form and to be oscillated about transverse axes.

6. The combination with a form for molding a concrete stair structure and having inner and outer forms forming casting cavities, of a mounting member on the outer form having spaced openings, bolts adapted to be passed inwardly through the openings into the cavities therebetween, removable means for retaining the said bolts in position in the mounting member, the said bolts being adapted to support threaded members between the forms and to leave said threaded members embedded in the cast structure when the bolts are subsequently removed, and the said bolts forming passages in the cast structure for the insertion of railing mounting bolts into engagement with the said threaded members.

7. A step mold of the character described for casting a series of steps, comprising forms for molding the component treads and risers of the steps, side plates arranged alongside the ends of said forms for closing off the ends thereof, and tie rods extending between the side plates for drawing the same tightly against the ends of the forms, the said forms being slidably supported at their ends between the side plates for adjustment when the tie rods are loosened.

8. A step mold of the character described for casting a series of steps, comprising forms for molding the component treads and risers of the steps, side plates arranged alongside the ends of said forms for closing off the ends thereof, the said side plates having longitudinally extending grooves, and lug members extending endwise from the forms and slidably and downwardly engaging the grooves in the side plates to support the forms therebetween.

9. A mold for casting a series of steps and comprising an outer form for molding the outer surface of the treads and risers, side members arranged alongside said outer form, separate trough-like inner forms for molding the inner surfaces of the treads and risers of each step,

cross members attached to said inner forms, and means for adjustably connecting the cross members to the side members to support said inner forms for adjustment lengthwise along the side members.

5 10. A mold for casting a series of steps and comprising an outer form for molding the outer surface of the treads and risers, side members arranged alongside said outer form, separate trough-like inner forms for molding the inner surfaces of the treads and risers of each step, said inner forms being positioned over the outer form in the casting position of the mold, and means supporting said inner forms for up and down adjustments with respect to the outer form to vary the thickness of the cast steps.

15 11. A mold for casting a series of steps and comprising an outer form for molding the outer surface of the treads and risers, side members arranged alongside said outer form, separate trough-like inner forms for molding the inner surfaces of the treads and risers of each step, and means supporting said inner forms for tilting adjustments about axes extending crosswise of the mold and to permit adjustments of the inner forms with respect to said outer form.

20 12. A mold adapted for casting a series of steps and side runners therefor, comprising forms arranged for molding the tread and riser surfaces of the steps, trough-like side forms arranged along the ends of the said tread and riser forms, said tread and riser forms being adjustable lengthwise of the side forms, and end closures supported from said tread and riser forms for adjustment therewith and engaged in said side forms for forming the ends thereof.

25 13. In a step mold including a form having a cavity for casting said steps, said form having an opening, adapted to receive a bolt so that its threaded end extends into the casting cavity, means on the form for rigidly engaging the bolt head and supporting the bolt in such position, a threaded member adapted to be screwed on the bolt end within the casting cavity to thereby become imbedded in the step, and said bolt head engaging means being releasable for removing the bolt from the form to thereby leave a passageway through which a railing mounting bolt may be screwed into the threaded member.

30 14. A mold for casting a series of stair steps and side runners extending lengthwise of the structure along the opposite ends of the steps, comprising center forms arranged for casting the component treads and risers of the steps, side forms arranged to cast the said side runners, and channel shaped means connecting the ends of the center forms and the side forms and spacing the side forms from said ends to thereby form gutters along inner edges of the side runners, said connecting means being so disposed that the gutters formed thereby will fall below the level of the ends of the step treads.

FRANK KOGL.
